UNITED STATES PATENT OFFICE

WILLIAM S. KELLOGG, OF PEORIA, ILLINOIS; HARRIET A. KEAS, ADMINISTRAATRIX OF
SAID WILLIAM S. KELLOGG, DECEASED

VARIABLE CONDENSER

Application filed September 24, 1927. Serial No. 221,776.

This invention pertains to improvements in variable condensers.

An object of the invention is to provide a condenser which includes a plurality of ro-

5 tor plates and stator plates wherein the several plates of said rotor plates may be operated serially throughout the entire number by control means in the hands of the opera-

tor.

10 Another object is to provide a condenser having a plurality of stator plates and rotor plates wherein said rotor plates are capable of operation independently of one another serially by an operating means common to all 15 of them, said means adapted for engaging of any one plate and carrying it into full mesh with the stator plates and then leaving it to engage a succeeding plate for a like action.

20 A further object is to produce a variable condenser which besides including a series of rotor plates capable of independent operation, also includes an operating means progressively movable through the condenser 25 to directly engage each plate in its order to carry the same wholly into mesh with the stator plates, or out of the same, throughout the entire series, and disengage from each plate as that action is accomplished.

30 Still another object is to provide a variable condenser wherein its rotor plates are movable independently of one another, and to furnish means for turning one or more of the plates in successive order into mesh with 35 the stator plates, said means progressively moving through the condenser and in such movement engaging a plate, turning it through its full movement, then disengaging from it and passing on to the next 40 throughout the series.

A still further object is to provide for a variable condenser having independently movable rotor plates an operating means to actuate each plate in turn whereby substantially the capacity required for a given 45 wave length results by the intermeshing of a required number of plates followed by the partial intermeshing of a further single plate to obtain perfect resonance.

50 Again, an object is to provide a type of

mechanism wherein movement of a rotating operating element for a series of members to be rotated is a progressive one axially of its mounting.

A further object is to provide a new type 55 of dial movement for a radio variable condenser combining a vernier portion for exact tuning.

In addition to the object above set forth the invention pertains to certain details of construction and arrangement of parts in a radio condenser of the variable type to be understood from the following description aided by the appended drawings wherein—

Figure 1 is a plan of my improved con- 60 denser.

Figure 2 is a side elevation of the same.

Figure 3 illustrates parts of the condenser in perspective.

Figure 4 is a plan of parts of said condenser 70 with portions shown in transverse section.

Figures 5 and 6 are elevations of a spacing member or washer to lie between the rotor plates of the condenser.

Figure 7 is a plan of parts shown in Figure 75 1 greatly enlarged.

Figures 8 and 9 are respectively a plan and end elevation of a spiral gear shown in Figures 1 and 7 produced on a scale corresponding to that in said Figure 7,

Figure 10 is an elevation of a form of dial 80 usable with the condenser of the type herein.

Figure 11 is a plan of a dial arrangement of a preferred form for use with my condenser.

Figure 12 is an elevation of the same.

Figure 13 is a transverse section of parts of said dial arrangement on line 13—13, Figure 12.

Figure 14 is a detail of parts of the dial 85 mechanism as seen in front elevation, and

Figure 15 is a transverse section of parts of the dial mechanism and the panel of a radio set.

I am fully aware of the fact that there is 90 no novelty in separately mounting and operating the rotor plates of a condenser but in so far as I am informed it is new to furnish mechanism operated by a dial-knob for successively carrying these plates into or out of 95 100

mesh with the stator plates, picking up one plate and turning it through its full movement and then leaving it to pick up the next. It is believed to be novel, also, to employ such mechanism to turn one or more plates to substantially the point of resonance of a radio receiver followed by the partial movement of another plate corresponding to a vernier adjustment for exact resonance, this being one of the purposes of my invention.

The condenser herein may be shielded and in conformity therewith a metal case is provided made up of a cylindrically curved lower one-half 1 and parallel side walls 2, 15 and an upper one-half 3, Figure 2, to engage with said lower half and secured by screws 4 for example.

Lying between said walls 2 and secured at their ends thereto in suitable manner are two 20 members 5 of insulating material between which is suspended a series of stator plates 6 in any usual manner, there being a metal cross member 7 connected to all of said plates from which extends a binding screw 8 insulated from the case, while a similar connection for grounding is provided at 9 on the said case 1, 2, Figure 1.

Extending centrally through the condenser space and secured to each wall 2 by the connection 9 and screw 10, for example, is a rod 11, Figure 4, overlying which is a tube 12 having a slot 13 therein extending lengthwise thereof, Figures 4 and 5.

The rotor plates of the condenser are denoted at 14. Each includes a central portion 15, Figure 3, having on its edge a series of teeth 16 in a semi-circular arrangement, Figure 2. Said portion 15 is provided with a hole 17 in the center from which all of the teeth 16 are equidistant, said hole being of a diameter to just receive the tube 12 in a smooth turning fit. The plates are adapted to slip upon said tube 12 spaced whereby each may pass between two of the stator plates 6 as in common practice. However, said plates are spaced from one another the required distance by the interposition of washers 18, Figures 5 and 6, each being prevented turning on the tube 12 by including a key-portion 19 to engage in the slot 13, but any equivalent method may be employed. Since the plates are adapted to turn independently it is required that no one of them shall affect another. Therefore, since the washers 18 are fixed with respect to the tube 12 any plate may be rotated without respect to others of the group. By placing the plates and washers upon the tube in alternate positions the desired spacing of the plates results. At 60 the back of the condenser a sleeve 20 may be placed over the tube 12 between the side 2 of the case 1, 2, and one of the washers 18, Figure 1, to form an abutment for the series of plates and washers, while at the front of 65 such condenser a spring 21 may be interposed

between the said series and the front side 2 of the condenser case thereby keeping all of the members of the group in snug order preserving the exact spacing of the plates.

Having thus mounted the plates, means 70 by which to operate them independently is provided to be understood from the following:

Extending between the plates 2 of the case and projecting through the front one there- 75 of is a threaded rod 22, which may be termed a thread-bar, secured to the back plate by a nut 23, as an example, said rod being held thereby from rotating. Overlying or enclosing the rod is a tube 24 slotted at 25 throughout, said tube likewise extending through the front plate of the condenser case, both the rod and tube likewise extending through the supporting panel 26 and a dial plate 25', the tube receiving upon it the 80 dialing knob 27 secured thereto in any suitable manner. Said tube is held in place against the back plate 2 of the case and prevented having endwise movement by a screw 28 which engages in the end of the thread- 85 bar 22 within the knob 27, the screw-head abutting upon said tube. Sleeved on the latter is the hub 29 of a spiral gear whose spirally arranged teeth are denoted at 30. The hub carries a pin 31 which extends 90 through the slot 25 of the tube 24 to engage between two of the threads of the thread-bar 22.

It is clear that in rotating the tube 24 on the fixed thread-bar the gear 29—30 rotating therewith will be carried along said tube due to the pin 31 following the threads of said thread-bar. When all of the rotor plates are fully disengaged from the stator plates the gear 29, 30 lies close to the front plate 2 free of all of the said rotor plates. Clockwise turning of the knob 27 advances the gear along the tube to cause it to mesh with the first plate. The relation of the teeth of the plate and gear, and the "lead" of the threads of the thread-bar is such that when the plate has been carried into full mesh with the stator the terminal tooth of said gear disengages from the teeth of the plate and the leading tooth of the gear has advanced into position to engage the teeth of the second plate, the described operation being repeated throughout the entire series of rotor plates, and obviously a counter-clockwise rotation of the knob 27 will reverse the operation fully disengaging the plates in the reverse order one by one.

When a number of plates are in mesh with the stator giving a certain capacity corresponding substantially with a given wave length it is clear that tuning to complete resonance can be accomplished by a partial movement of an additional plate for a required small additional capacity with great exactness and an exactness not possible with 130

any condenser of which I am aware. That is to say, by reason of the fact that I am enabled to operate each and every rotor plate by direct control through a dial-knob and the gear 29, 30, or its equivalent, an exactness of adjustment is assured.

A multiple condenser such as a three gang condenser, for example, may be constructed by coupling several of the tubes 24 together or by using a single tube extending through all of the condenser bodies, this not having been shown however, and the same tuning can be accomplished. But the advantage of my method of operation in connection with such gang arrangement will now be evident. In order that the capacities of all of the condensers of the gang may be identical so that loggings of the several dials of a radio set will correspond, one of the plates of any condenser may be advanced by hand a distance of one or more teeth, or to such position, at least, that the several capacities will agree and there left, the spiral gear picking up the plate in its regular travel through the condenser but always leaving it in the hand-adjusted position after each operation thereof.

Due to the fact that the dial-knob in my condenser must turn through a plurality of rotations, in this instance a complete revolution to a one-half rotation of a rotor plate, a type of dial is required over which to spread station readings. Therefore merely as showing a manner of doing this the dial plate 25' previously referred to is carried on the tube 24 to rotate with it and the knob 27. In its rear face it may have a spiral groove 27' indicated in broken lines in Figure 10. An arm 32 is pivotally mounted on the panel 26 and a pin 33 on its free end, Figure 1, may engage in the groove, and an indicator-arm 34 fixed with respect to said arm 32 swings over the face of the dial describing a spiral path in the rotation of the latter and at the extremity of which station readings may be made. Pins 35 for example carried by the dial serve as stops at the ends of dial rotation, the same adapted to abut upon said arm 34.

In Figures 11 to 15 the preferred form of dial arrangement is shown, however, wherein, as before, 26 designates the panel for supporting the condenser. And in this instance the latter by choice has been rotated to the right sufficiently to station the knob 27' at the bottom of the dial 36, this being merely for appearance sake.

Said dial consists of a ring which rotates upon or about a disc 37, for example, secured on the panel 26. The inner edge of the ring is provided with equally spaced notches 38 to separately receive a pin 38' carried by the said knob 27' which pin acts after the manner of a gear tooth by entering a notch 38 in each rotation of such knob. The disc 37 is

cut away at 37' to permit the orbital movement of said pin 38'. A cover-plate overlies the dial 36 and is also cut away at 36' for the same reason as just given, while screws 40 may extend through the cover-plate and disc into the panel 26 securing the parts in place. The tube 24 and thread-bar 22 extend through the cover plate and receive the said knob 27', the latter covering the openings 36' and 37'. The knob carries any usual portion 27' which may be provided with indicating marks extending entirely around it numbered from 0 to 100, as an example, any mark being brought opposite a mark 41 on the cover-plate 39. In the latter is a window 42 through which station indications on the dial 36 may be read, and said indications may represent meters or station signatures.

In operation, one full rotation of the knob will advance the dial one position opposite the window 42 due to the engagement of the pin 38' with one of the notches 38. It is clear that one full rotation of the knob will impart a full one-half turn to any plate 14 added to which, a station having been partially "brought in" by that movement of the plate, a further turn of the knob will advance a succeeding plate to a point of full resonance whereupon the reading will be at both the window 42 and at the knob answering admirably as a vernier dial arrangement.

The station indications or meter readings may extend entirely around the dial, i. e., in a full circle, this depending upon the number of rotor plates employed and the rate of advance of the dial through the pin 38'. That is to say, the rate of step by step advancement of the dial hinges upon the distance said dial travels at each engagement of said pin. Otherwise stated, as the pin more closely approaches the center of knob rotation the less distance of travel will be imparted to the dial.

I claim:

1. In a variable condenser, in combination with the rotor thereof whose plates are independently movable, mechanism including a member mounted to travel substantially parallel to the axis of mounting of the plates adapted to engage with and operate each plate independently and in successive order and after each such operation disengage therefrom.

2. In a variable condenser, in combination with independently movable rotor plates, mechanism including a member adapted to advance through the condenser substantially parallel to the axis of mounting of said plates, and adapted to positively engage and transmit movement to a plate and then disengage therefrom before engaging a succeeding plate.

3. In a variable condenser, in combination with independently movable rotor plates, mechanism including a member mounted for

progressive movement through the series thereof in a direction substantially paralleling their axes adapted to engage and operate a single plate and to disengage therefrom after full meshing of said plate with the stator plates of such condenser.

4. In combination with the stator plates and the independently rotatable plates of a variable condenser, mechanism including a member mounted for progressive movement in a direction paralleling the axis of said rotatable plates adapted to engage and operate each plate independently and in successive order both into and out of mesh with said stator plates.

5. In combination with the stator plates and the independently rotatable plates of a variable condenser, mechanism including a member mounted for progressive movement in a direction paralleling the axis of said rotatable plates adapted to engage and operate each plate independently and in successive order into mesh with the said stator plates in one direction of movement of said member, and to unmesh the same in a reverse direction of its movement.

6. In combination with the stator plates and independently movable rotor plates of a variable condenser, mechanism including a rotatable toothed member mounted for movement progressively through the condenser in a direction substantially paralleling the axis of mounting of said rotor plates, the said rotor plates each having teeth adapted to be successively and independently engaged by the member whereby to turn said plates independently and in successive order into mesh with the stator plates.

7. In combination with the stator and independently movable rotor plates of a variable condenser, a rotatable toothed member mounted for movement progressively past said rotor plates, a series of teeth on each of the latter, the teeth of one of the described elements being spirally arranged, and means manually operated to advance the member through said condenser.

8. In combination with the stator and independently movable rotor plates of a variable condenser, means mounted for progressive travel through the condenser in a direction at right angles to the planes of the plates adapted to positively engage and carry said rotor plates independently and in serial order into mesh with the stator, and also adapted to disengage from each rotor plate in succession after such meshing.

9. In combination with the independently movable plates of a variable condenser, a member mounted for progressive movement through the condenser in a direction at right angles to the planes of said plates adapted to engage and impart positive movement to each plate independently and in successive

order and to disengage from one plate before engaging a succeeding one.

10. In combination with a series of independently movable rotor plates in a variable condenser, each said plate having a series of teeth disposed thereon in a semi-circular line, a rotatable toothed member, a mounting for said member adapted to carry the same progressively through the condenser, said member adapted to engage and operate each plate in successive order and to disengage from one before engaging the next.

11. In a radio condenser, the combination of a pair of spaced rotatable condenser plates mounted on a common axis, each having a series of teeth arranged concentrically of said axis, a sleeve having a series of teeth arranged thereon in a spiral adapted to engage the teeth of the plates, and a mounting for the sleeve adapted to advance the latter in a line paralleling the said axis of the said plates.

12. In a radio condenser, the combination of a pair of spaced independently rotatable condenser plates mounted on a common axis and each having a series of teeth arranged concentrically of said axis, a sleeve having a series of teeth arranged about the same and engageable with the teeth of the plates in serial order independently, and a mounting for the sleeve adapted to advance the latter in a line paralleling said axis of said plates.

13. In combination with a series of independently rotatable rotor plates in a variable condenser, each plate having a series of teeth disposed thereon in a semi-circular line, a mounted thread-bar extending through the condenser, a tube enclosing the thread-bar and having a slot extending longitudinally thereof opening upon said thread-bar, a toothed member carried by the tube rotatable therewith and engaging the thread-bar adapted in the rotation of the tube to move through the condenser and engage the teeth of one of the plates and also adapted after imparting a full turn to said plate to disengage therefrom.

14. In combination with a series of independently rotatable rotor plates in a variable condenser, each plate having a series of teeth disposed thereon in a semi-circular line, a mounted thread-bar extending through the condenser, a tube enclosing the thread-bar and having a slot extending longitudinally thereof opening upon said thread-bar, a member carried by the tube rotatable therewith having teeth thereon, arranged in a spiral, said member engaging the thread-bar through said slot, said teeth of the member adapted in the rotation of the said tube to travel progressively through the condenser and to engage the teeth of one of the plates and also adapted after imparting a full turn to said plate to disengage therefrom.

15. In combination with a series of independently rotatable rotor plates in a variable condenser, each said plate having a series of teeth disposed thereon in a semi-circular line, a thread-bar extending through the condenser fixed with respect to the body thereof, a tube enclosing the thread-bar adapted to rotate thereon and having a slot extending longitudinally thereof opening upon the thread-bar, a toothed member encircling the tube adapted to mesh with the teeth of the rotor plates, said member engaging the thread-bar through said slot, and an operating dial-knob fixed on the tube.
16. In combination, a thread-bar, a member paralleling the same and rotatable about it, a sleeve having a projection to engage the threads of said thread-bar, means to prevent the sleeve and member from rotating relatively but permitting said sleeve to move longitudinally of the latter, both the sleeve and member adapted to rotate together with respect to the said thread-bar.
17. In combination, a thread-bar, a tube enclosing the same having a slot extending longitudinally thereof opening upon the thread-bar, and a toothed sleeve encircling the tube engaging the said thread-bar, the tube and sleeve adapted to rotate together with respect to the said thread-bar.
18. In combination, a thread-bar, a tube encircling and rotatable about the same and having an opening extending along one side thereof, a toothed sleeve encircling the tube, and means on the sleeve extending through the opening of said tube and engaging the said thread-bar, the tube and sleeve adapted to rotate together with respect to the thread-bar, and said sleeve adapted to move longitudinally of both the tube and thread-bar.
19. In combination with independently movable rotor plates of a variable condenser, a member mounted for rotative movement progressively through the condenser in a direction at right angles to the planes of said plates adapted and arranged to positively engage and impart rotative movement to each plate in its order and to disengage from one plate before engaging a succeeding one.
- In testimony whereof I affix my signature.
WILLIAM S. KELLOGG.
